Perreault & Pfleger, PLLC**CLAIM**

The ornamental design for a welding torch component, as shown.

DESCRIPTION

FIG. 1 is a rear end view of the welding torch component of the present invention;

FIG. 2 is a side view of the welding torch component of FIG. 1; and,

FIG. 3 is a perspective view of the welding torch component of FIG. 1.

The drawings represented in FIGS. 1-3 disclose the complete appearance of the design, as the side view is identical around the entire circumference.

Broken lines in the drawings represent unclaimed environmental subject matter.
